UNITED STATES PATENT OFFICE.

FRANK A. FUCI AND WILLIAM ZEUNGES, OF PITTSBURGH, PENNSYLVANIA.

MEANS FOR COVERING AND FASTENING MILK CASES AND THE LIKE.

Application filed September 20, 1921. Serial No. 501,962.

To all whom it may concern:

Be it known that we, FRANK A. Fuci and WILLIAM ZEUNGES, citizens of the United States, and residing in the city of Pittsburgh, in the county of Allegheny and State of Pennsylvania, have invented or discovered new, useful, and Improved Means for Covering and Fastening Milk Cases and the like, of which the following is a specification.

Our invention consists of new and improved closure means for containers, such as milk bottle cases and the like, and also for locking a plurality of such cases in stacked relation so that they may be portable as a unit.

More particularly speaking, said means consists of a lid which, in the case of a single case, is placed on the case, and a chain which is stretched across said lid to hold it in position, one end of said chain being connected to a hook member which engages the bottom edge of the case or the hand slot at one end, while the other end of said chain is connected to one end of a stretching bar which is pivotally mounted on a second hook member engaging the other end of the case, said stretching bar being then reversed to tighten the chain and being locked in position.

Where a plurality of cases are to be locked together in stacked relation, said cases are first stacked, with the usual corner posts of the cases extending up into the corners of the case next above to hold the cases in alinement. The lid is then placed on the top case and the chain stretched across the same, the hook members to which the ends of the chain are attached engaging the bottom edges or hand slots of the bottom case.

In the accompanying drawings, Fig. 1 is a perspective view showing our invention applied to a stack of two cases; Fig. 2 is a cross section of a single case showing our invention applied; Fig. 3 is an inverted plan view of the form of lid which we prefer to use; Fig. 4 is an enlarged perspective showing the hook member which is provided with chain tightening and locking means; Fig. 5 is a side view of the same on smaller scale, the end of the chain being shown engaged, tightened and locked, the chain being shown untightened and unlocked in Fig. 2, and Fig. 6 is a rear elevation of the other hook member.

The following is a detailed description of the drawings.

A represents a milk bottle case, two being shown stacked together in Fig. 1, while a single case is shown in Fig. 2. Said cases are usually provided with open work bottoms, such as the wires or bars 1 spaced somewhat above the bottom edge of the case, while the interior of said case is divided into nests or sockets for the bottles, as by means of the horizontal crossed wires or bars 2 and 3. The upper corners of said cases are usually provided with upwardly extending posts 4 which fit into the bottom corners of the second case superimposed on the bottom case, thus facilitating stacking by maintaining the cases in alinement.

We provide a lid B which, in the case of a single case, is placed on top of the same, as shown in Fig. 2, while in the case of a stack of cases, as in Fig. 1, is placed on top of the top case. Said lid is preferably made of a metal plate and has its corners cut away, as at 5, to provide clearance for the upward protrusion of the posts 4. The lateral edges of the lid B are bent downwardly to form the flanges 6 which fit down over the top sides of the case, and the ends of said lid are provided with the pairs of horizontally projecting ears 7 which are spaced apart to form the guide slots 8 for the chain C.

We provide a pair of hook members, preferably made of bent metal, for the ends of the chain. Thus D is a hook member to whose shank 9 one end of the chain is permanently secured, the hook end 10 of said member engaging the bottom edge of the case A at one end of the latter. The end of said member is preferably slotted or bifurcated, as at 11, so that it may extend upwardly through the open work bottom of the case. The other hook member E is of somewhat similar construction and which engages the opposite bottom edge of the case. The member E is not however directly connected to the chain, but to its outer face is attached a bracket 12 having outwardly extending and spaced apart flanges 13 for the support of the pivot pin 14 whose ends extend through alined holes in said flanges and may be riveted to hold the pin in place.

F is a bar pivotally mounted intermediate of its ends on the pin 14, washers 15 being mounted on said pin on either side of the

bar to hold the latter in proper position. One end, marked 16, of said bar F is hooked to engage a link in the chain C while the other, and preferably the longer end is provided with a hole 17 for the hasp of a padlock G. When not in use the bar F is positioned with its hooked end upwardly.

When in use as a closure for a single case, the lid B is put in position, and the 10 hook member D, to which one end of the chain C is permanently attached is engaged under the bottom edge of the case A, as shown in Fig. 2, and the chain is drawn over the lid through the guide slots 15 8 and inserted down between the flanges 13 in the rear of the pin 14 and its adjacent link engaged by the hooked end of the bar F. The bar F is then reversed from its position shown in Fig. 2 into the 20 position shown in Fig. 5, its hooked end being thus depressed, thereby tightening the chain across the lid. The hasp of the padlock G is then inserted through the 25 hole 17 in the bar F and through the adjacent link of the chain C, and the padlock snapped closed.

Where a stack of cases, as in Fig. 1, is to be closed and locked, the lid B is placed on the top case, the hook member D is engaged with the bottom edge of the bottom case, or, as is preferable, in the hand slot 30 18 in the end of the bottom case. The chain is then led up the stack and across the lid and down the other end, and the chain is engaged by the hooked end of the bar F 35 of the hook member E which is engaged with the hand hole in the end of the bottom case. The bar F is then reversed and locked, as already described.

40 If desired, the chain C may be of sufficient length, as shown in Fig. 1, to be padlocked to a post or other permanent structure, to prevent the case or stack of cases being removed by unauthorized persons.

45 We prefer to provide the under face of the lid B with a spring clip 19 under which a bill or other note or communication may be slipped.

50 It is evident that our invention provides a safe and convenient method of covering and locking either individual cases or a stack of the same, so that they may be conveniently loaded and unloaded from a vehicle and generally handled without danger of breakage, and so that stealing of the 55 bottles or cases, after delivery is prevented.

What we desire to claim is:—

60 1. Means for closing and locking a case of the character described which consists in the combination of a lid adapted to fit on top of the case and held against lateral displacement, a hook member engaging one end of said case, a second hook member engaging the other end of said case, a bar 65 pivotally mounted intermediate of its ends

on said second hook member and provided with a hooked end, a chain having one end attached to said first named hook member and led across said lid and having its other end portion engaged by the hooked end of said bar, whereby by reversing said bar said chain is stretched taut across said lid, and means for locking said bar in its reversed position.

2. Means for closing and locking a case of 75 the character described which consists in the combination of a lid adapted to fit on top of the case and provided at its ends with chain notches, a hook member engaging one end of said case, a second hook member engaging the other end of said case, a bar pivotally mounted intermediate of its ends 80 on said second hook member and provided with a hooked end, a chain having one end attached to said first hook member and led across said lid, seating in said notches, and having its other end portion engaged by the hooked end of said bar, whereby by reversing said bar said chain is stretched taut across said lid, and means for locking 85 said bar in its reversed position.

3. Means for closing and locking a case of the character described which consists in the combination of a lid adapted to fit on top of the case and held against lateral 95 displacement and provided at its ends with chain notches, a hook member engaging one end of said case, a second hook member engaging the other end of said case, a bar pivotally mounted intermediate of its ends 100 on said second hook member and provided with a hooked end, a chain having one end attached to said first hook member and led across said lid, seating in said notches, and having its other end portion engaged by 105 the hooked end of said bar, whereby by reversing said bar said chain is stretched taut across said lid, and means for locking said bar in its reversed position.

4. Means for closing and locking a 110 case of the character described which consists in the combination of a lid adapted to fit on top of the case and held against lateral displacement, a hook member engaging one end of said case, a second hook member 115 engaging the other end of said case, a bar pivotally mounted intermediate of its ends on said second hook member and provided with a hooked end, a chain having one end attached to said first named hook 120 member and led across said lid and having its other end portion engaged by the hooked end of said bar, whereby by reversing said bar said chain is stretched taut across said lid, and means for locking said bar in its 125 reversed position, one end of said chain being prolonged for locking to a fixed object to prevent unauthorized removal of the case.

5. Means for closing and locking together a stack of cases superimposed one on the 130

other, which consists in the combination of a lid fitting on top of the top case, a hook member engaging one end of the bottom case, a second hook member engaging the 5 other end of the bottom case, a bar pivotally mounted intermediate of its ends on said second hook member and having a hooked end, a chain having one end attached to said first named hook member and led across said lid 10 and having its other end portion engaged by the hooked end of said bar, whereby by reversing said bar said chain is stretched taut, clamping said cases together in stack formation and clamping said lid on said top case, 15 and means for locking said bar in its reversed position.

6. Means for closing and locking together a stack of cases superimposed one on the other, which consists in the combination of 20 a lid fitting on top of the top case, a hook member engaging one end of the bottom case, a second hook member engaging the other end of the bottom case, a bar pivotally mounted intermediate of its ends on said second hook member and having a hooked end, a chain having one end attached to said first named hook member and led across said lid and having its other end portion engaged by the hooked end of said bar, whereby by reversing said bar said chain is stretched taut, clamping said cases together in stack formation and clamping said lid on said top case, 25 and means for locking said bar in its reversed position, one end of said chain being prolonged for locking to a fixed object to prevent the unauthorized removal of said cases.

7. Means for closing and locking together a stack of cases superimposed one on the other, which consists in the combination of 40 a lid fitting on top of the top case and held against lateral displacement, a hook member engaging one end of the bottom case, a second hook member engaging the other end of the bottom case, a bar pivotally mounted intermediate of its ends on said second hook member and having a hooked end, a chain having one end attached to said first hook member and led across said lid and having 45 its other end portion engaged by the hooked end of said bar, whereby by reversing said bar said chain is stretched taut and said cases are clamped together in stack formation and said lid is clamped on said top case, 50 and means for locking said bar in its reversed position.

8. Means for closing and locking together a stack of cases superimposed one on the other, which consists in the combination of 60 a lid fitting on top of the top case and held against lateral displacement, a hook member engaging one end of the bottom case, a second hook member engaging the other end of the bottom case, a bar pivotally mounted intermediate of its ends on said second hook

member and having a hooked end, a chain having one end attached to said first hook member and led across said lid and having its other end portion engaged by the hooked end of said bar, whereby by reversing said bar said chain is stretched taut and said cases are clamped together in stack formation and said lid is clamped on said top case, and means for locking said bar in its reversed position, one end of said chain being prolonged for locking to a fixed object to prevent unauthorized removal of said cases. 70 75

9. Means for closing and locking together a stack of cases superimposed one on the other, which consists in the combination of a lid fitting on the top case and held against lateral displacement, said lid being provided at its ends with chain notches, a hook member engaging one end of the bottom case, a second hook member engaging the other end of the bottom case, a bar pivotally mounted intermediate of its ends on said second hook member, a chain having one end attached to said first hook member and led across said lid and having its other end portion engaged by the hooked end of said bar, whereby by reversing said bar said chain is stretched taut, clamping said cases together in stacked relation and clamping said lid on the top 90 95 case, and means for locking said bar in its reversed position.

10. Means for closing and locking together a stack of cases superimposed one on the other, which consists in the combination of a lid fitting on the top case and held against lateral displacement, said lid being provided at its ends with chain notches, a hook member engaging one end of the bottom case, a second hook member engaging the other end of the bottom case, a bar pivotally mounted intermediate of its ends on said second hook member, a chain having one end attached to said first hook member and led across said lid and having its other end portion engaged by the hooked end of said bar, whereby by reversing said bar said chain is stretched taut, clamping said cases together in stacked relation and clamping said lid on the top case, and means for locking said bar in its reversed position, one end of said chain being prolonged for locking to a fixed object to prevent unauthorized removal of the cases. 100 105 110 115

11. Means for closing and locking a case of the character described which consists in the combination of a lid adapted to fit on top of the case and held against lateral displacement, a hook member engaging one end of said case, a second hook member engaging the other end of said case, a bar pivotally attached to one of said hook members, a chain connected to the other hook member and led across said lid and having the bar engaging its other end por- 120 125 130

tion whereby by reversing said bar said chain is stretched taut across said lid, and means for locking said bar in its reversed position.

5 12. Means for closing and locking together a stack of cases superimposed one on the other, which consists in the combination of a lid fitting on top of the top case and held against lateral displacement, a hook member engaging one end of the bottom case of the stack, a second hook member engaging the other end of said bottom case, a bar pivotally attached to one of said hook mem-

bers, a chain having one end connected to the other hook member and led across said lid and having its other end portion engaged by said bar, whereby by reversing said bar said chain is stretched taut, clamping said cases together in stack formation and clamping the lid on the top case of the stack, and means for locking said bar in its reversed position.

Signed at Pittsburgh, Pa., this 16th day of Sept., 1921.

FRANK A. FUCI.
WILLIAM ZEUNGES.
